UNITED STATES PATENT OFFICE.

SAMUEL L. P. GARRETT, OF LEWISBURG, TENNESSEE.

RAILROAD-GATE.

SPECIFICATION forming part of Letters Patent No. 226,299, dated April 6, 1880.

Application filed September 5, 1879.

To all whom it may concern:

Be it known that I, SAMUEL LOGAN PLEAS-
ENT GARRETT, of Lewisburg, in the county
of Marshall and State of Tennessee, have in-
5 vented a new and Improved Railroad-Gate,
of which the following is a specification.

Figure 1 is a plan view of the operative
mechanism of the gate. Fig. 2 is a front ele-
10 vation of the gate, with the box inclosing the
mechanism partly broken away to exhibit the
same. Fig. 3 is a side elevation of some parts
of the mechanism.

Similar letters of reference indicate corre-
sponding parts.
15 The object of this invention is to provide a
railroad-gate that an approaching train will
open by the pressure of the flanges of the
wheels upon a horizontal bar fixed parallel
with the rails and rising a little above them.
20 The invention consists in the combination,
with railroad-gates, of lazy-tong levers oper-
ated by the wheels of cars in such a way that
when the wheel depresses levers the lazy-tongs
spread and throw open the gates, the latter
25 being so arranged as to close by their own
gravity, all as hereinafter described.

In the drawings, A A represent the gate-
posts, carrying on their faces the sheaves B B.
30 C C are the gate-sections, provided with lon-
gitudinal slots D D, in which the sheaves B B
engage. E E are the railroad-rails. F is the
bar set on the upper ends of the vertical bars
G G, and extended on each side of the gates,
35 and so placed as to receive the pressure of the
flanges of the car-wheels as they pass over
the rails E E. This bar G is jointed at a',
and is flexibly connected at a'' to an arm on
the rocking shaft H, that is journaled in the
40 cleats I I. At the center of the shaft H, and
to an arm thereon, is jointed the bar K, whose
other end is attached to side prolongations of
the compound lever or lazy-tongs L, which is
centrally pivoted at x on a fixed standard or
45 base beneath it. The other ends of the lazy-
tongs L connect at y with the upward-curved

rods M M, that carry within their loops b' b'
the sheaves N N, and whose upward-project-
ing ends are fastened to the lower and outer
corners of the gate-sections C C.

In order to avoid friction and for the proper 50
support of these curved rods M M, the rails
O O are provided for the sheaves N N to rest
and run upon.

When the gate is closed the flanges of the
car-wheels running on the track will press 55
upon the bar F, which, in turn, will bear down
upon the bars G G and cause them to turn
the shaft H inward, so that the bars K shall
quickly force outward the end of the lazy-
60 tongs L and the curved rods M M, that are
fastened to the gate-sections C C. Thus the
gate is instantly opened, the sections C C be-
ing drawn apart, and is so retained by the
pressure of the wheels upon the bar F until
65 the train has passed, when their own weight
(the weight of the sections C C) and their in-
ward inclination cause them to close again.
If the bar F be placed outside of the rail E it
must be set higher, so that the overhanging
70 tread of the wheels may press upon it.

All the levers and bars may readily be boxed
in for protection from snow, so that they will
be in condition to operate at any time.

Having thus described my invention, I claim
as new and desire to secure by Letters Pat- 75
ent—

1. The gate-posts A A, sheaves B B, gate-
sections C C, provided with slots D D, bar F,
bars G G K K, lazy-tongs L, rocking shafts
H H, curved rods M M, sheaves N N, and 80
rails O O, constructed and arranged substan-
tially as herein shown, and for the purpose
described.

2. The combination of the lever or lazy-
tongs L with rods M M and sheaves N N, 85
substantially as herein shown and described.

SAMUEL LOGAN PLEASENT GARRETT.
